UNITED STATES PATENT OFFICE.

HUBERT F. KRANTZ, OF BROOKLYN, NEW YORK, ASSIGNOR TO KRANTZ MANUFACTURING COMPANY, INC., OF BROOKLYN, NEW YORK, A CORPORATION OF NEW YORK.

REMOVABLE SAFETY-SWITCH.

1,292,806.

Specification of Letters Patent.

Patented Jan. 28, 1919.

Original application filed July 31, 1915, Serial No. 42,956. Divided and this application filed March 31, 1916. Serial No. 87,925.

To all whom it may concern:

Be it known that I, HUBERT F. KRANTZ, a citizen of the United States, and residing at Brooklyn, in the county of Kings and State of New York, have invented a new and Improved Removable Safety-Switch, of which the following specification is a full disclosure.

This application is a division of my co-pending case, No. 42,956, filed July 31st, 1915, and it proposes certain improvements in switch mechanisms insuring the operation thereof against accidents while at the same time affording facilities whereby certain parts may be readily inspected and renewed.

One object of this invention is to render available a switch mechanism in the nature of a panel board so designed and constructed that an ordinary unskilled user will be barred from access to the switch blades and the contacts therefor as well as from the replaceable fuse elements, thereby not only preventing him from injuring himself but also preventing from surreptitiously substituting improper fuse elements while yet enabling him freely to open or close the switches.

Another object is to provide a panel board whereby the janitor of a building, or other similarly qualified person may have access to the replaceable fuse elements, but only when the circuit thereof is "dead," so that he will be unable to strike an arc by withdrawing the fuse from a live circuit.

Another object is so to design the panel board that a regular inspector may have access to all parts of the device, especially so that the switch blades and their immediate operating parts may be removed as units and may be examined away from the panel board or replaced by similar units.

A still further improvement insures that the switch shall be in "open" position and with the circuit thereof "dead" before enabling the switch unit to be removed; thereby preventing the inspector from being injured or from damaging any of the parts by opening the circuit in such a way as to draw an arc.

A still further object of this invention is to devise a panel board arrangement such

that a magnetic blow-out of the spark will be insured.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views, of which:

Figure 1 is a sectional plan showing one form of panel board conforming to this invention; parts being cut away to show the interior thereof. Fig. 2 is a longitudinal section through line 2—2 of Fig. 1 showing further details thereof. Fig. 3 is a side elevation partly in section of a removable switch unit suitable for employment in the panel board shown by Figs. 1 and 2. Fig. 4 is an end elevation partly in section of Fig. 3, as seen along line 4—4 thereof. Fig. 5 is a modified removable unit construction showing a somewhat different switch mechanism, also capable for use in connection with the panel board illustrated by Figs. 1 and 2. Fig. 6 is an end elevation of Fig. 5 taken partly in section as seen along line 6—6 thereof. Fig. 7 is a wiring diagram.

Continuing now by way of a more detailed description, A denotes a panel box consisting of a suitable base board 1, side walls 2 and end walls 3, either stamped up integrally of sheet metal or built up separately of pieces of insulating material, according to preference. This panel box preferably provides several separate compartments, *i. e.*, a gutter B for various line terminals; one or more switch compartments C; one or more fuse compartments D; and a switch actuator

ing compartment E which may be permanently opened or may be closed by an outer door if desired. Preferably these are separated from one another as by means of partitions 4, 5, 6, etc., and they are all separated from the outer switch controlling compartment E so that access to the interior thereof may be had but not with equal facility in each instance. That is to say, the terminal 10 compartment B will need to be opened only at rather infrequent intervals, and it is, therefore, proposed to close the same by means of a lid 7 held in place by screws 8 and 9. On the other hand the fuse containing compartment D may require entry quite frequently by the janitor of the building and in this embodiment of this invention it is closed by means of a door 10 hinged at 11 and provided with a catch 12 whereby it 15 may be locked in place under conditions shortly to be mentioned. A handle 13 may be used for opening and closing this door. The compartment C contains switch-operating elements of a unitary construction and 20 each may be removed as a unit by the inspector whenever necessary, and to that end these parts may be held in place by ordinary screws in such a way that their removal can be easily accomplished with the proper implements. These removable units will now 25 be described.

A removable switch-unit is shown best by Figs. 2, 3 and 4 and is indicated generally by F on Fig. 2, and it comprises a suspension plate or base 14 which is suitably configurated so that it may be interlocked in place; as for example, by means of screws 15. This base plate provides the ultimate mounting for the switch mechanism *per se* but preferably it does not provide the contacts for the switch blades. In the preferred form of unit, the switch blade is of laminated construction as indicated by 16, being composed of copper strips arranged echelon so as to produce oppositely angled beveled ends, and the outer strips 17 and 18 may be of heavier construction and may carry pieces 19 which are made sufficiently durable to endure the spark. Clamping plates 20 and 21 of suitable insulating material are secured to a swinging block 22 by means of bolts 23. These blocks 22 have side flanges 24 which are perforated to receive a shaft 25, which in turn passes 30 through the sides 26 of a supporting frame 27 secured to the base plate 14 by means of screws 28. Two disks 29 of insulating material will prevent the switch blades 16 from coming into contact sidewise with the supporting frame 26. The means for controlling the swing of the switch blade 16 will 35 not be described.

An arm 30 extends radially from the swinging block 22 and is apertured to provide the internal cam indicated by 31. This

cam co-acts with a roller 32 pivoted to the end 33 of a hand lever G which is pivoted by means of a stud 34 to the side walls 26 of a supporting frame 27. This internal cam 31 is so contoured that when the parts 70 are in the position shown by Fig. 3 the switch blade will be sprung against a post 35 so as to impose a stress on all of the parts and enable them to remain in the position as shown. This is achieved by designing the cam at the point 36 in such a way that a tendency of the switch blade to move clockwise under the re-action against the post 35 will tend to hold or swing the lever G clockwise also; with the result that 75 the parts will be in stable position. This represents the "dead" or open circuit position of the switch unit, and the advantage of this construction is that when the unit is removed and handled when in this position, it tends to remain thus set or locked, and the attendant is thus enabled to replace the unit in the same relation that it is removed.

In replacing the unit, it is only necessary 90 to thrust the lower part thereof through the aperture providing admission to the compartment C and then by means of screws 15 to bolt the base plate 14 of the unit to the parts 27 and 38; whereupon the switch 95 is ready for operation. In operation the insulating handle 40, which is secured to the exposed end of the lever G, is turned anti-clockwise. The effect of this is first to break the set or lock above noted and forthwith to swing the switch blade clockwise until its one end bears against the main-line contact piece H and its other end against the contact piece I forming part of the branch-line electrical conductors. This 100 immediately establishes electrical connection between the contact terminals I and H.

It may be noted that as the handle 40 enters its final position when turned anti-clockwise the blade will be sprung against these contacts and held in that position by means of the peculiar contour of the cam at the point 41; or conversely as already explained. The effect of this is not only to lock the switch blades firmly against their electrical contacts but also to insure a quick break when the handle 40 is swung clockwise to open the circuit. The quick break effect is preferably further accentuated by means of a magnetic blow-out as follows: 110 The conductor I is connected by means of a copper strip 42 with the ribbon or wire 43 forming the winding of an electromagnet J which has its core or armature 44 connected with pole pieces 45 which terminate at 115 the arcing region of the terminal I. By this arrangement a magnetic field is set up across the path of movement of the switch blade 16 so that when the circuit is broken the 120 arc will be blown out magnetically. 130

The terminal I delivers its current through the intermediary of a conductor 46 (which is connected with the clip 47) to the fuse K. A similar clip 48 at the other end 5 of the fuse provides a path for the flow of the current to other connections or terminals as may be desired.

Reverting now to the switch unit, it is to be noted that a movable tongue L is so positioned during the actuation of the switch as to control the opening of the door 10, and preferably also to prevent the removal of the switch unit. In this instance this is accomplished by pivoting the tongue L at 50 to 15 the link G and providing it with a slideway 51 coöperating with the stud 52 so that the tongue L will be withdrawn or retracted from its effective position when the switch is set into its dead position; and so that it 20 will be projected into its effective position when the switch has been moved or set into its live position. That is to say, when the switch is dead the tongue L will be in the position shown by Fig. 2; but when the 25 switch is turned "on" the tongue L will project underneath the part 38, and will thus prevent the base-board 14 from being lifted up and away from said part; even though the screw 15 be removed. When the switch 30 is in this position the blade 16 will also bear against the normally live terminal H in such a way that the other end of the base 14 cannot be lifted up for a similar reason. This construction, therefore, prevents the switch 35 from being removed when it is in live position.

The means locking the door to the fuse compartment will now be described. A spring latch M is mounted on the cross piece 40 33 in such a manner that it may slide back and forth and this latch terminates in a head 54 which is beveled and which may enter the adjacent aperture or socket 12 in a catch depending from the door 10 and thus 45 prevent the door from being opened. Normally a spring 55 presses against the head 56 and holds the latch 54 in the position shown by Fig. 2, but when the switch is closed the tongue L will project against the head 56 and urge the latch 54 into a position 50 preventing any opening of the door 10.

The switch shown by Figs. 3 and 4 is of such a construction that springs may be dispensed with entirely, if desired, because the 55 parts may be held in either one of their two extreme positions through pressures derived from the resilient switch blade 16, which, in its one position is sprung against the circuit contacts, and in its other position is sprung 60 against the post 35. At the same time this switch provides a sufficiently quick break for all practical purposes, especially in coöperation with the magnetic blow-out. In case a mechanically quicker switch should be desired, this unit may be interchanged by the 65

spring actuated unit set forth in Figs. 5 and 6.

The detachable spring actuated switch mechanism shown by Figs. 5 and 6 may be successfully used for all purposes with a 70 magnetic blow-out, and for even most purposes without a magnetic blow-out. This unit comprises a frame denoted generally by the character N, and which may be built of a number of parts, as for example, the face 75 plate 60 of insulating material and the metallic side flanges 61 connected thereto by means of the plate 62 and the screws 63. This face plate 60 is in turn contoured to interfit with the opening provided by the 80 stationary supporting part or parts 64, which correspond with the parts 37 and 38 of Fig. 1; screws 65, or other conventional means, being used to retain these elements together temporarily. The face plate 60 is here 85 formed with two segmental lips 55, supported by a slot 67 through which the shank 68 of an operating handle O emerges. This shank terminates at the exposed side of the face plate 60 in a suitable hand grip 69 90 whereby the switch mechanism may be operated, as will be understood. This shank is preferably pivoted about the shaft x which constitutes the fixed or stationary pivot of a toggle which is broken and closed by the 95 handle O.

The other main operative elements are the non-floating swinging links P P', the floating links Q Q', the swinging blade carrier R and the switch blade S. The links P and Q constitute a toggle which, when broken, permits the blade or brush S to assume its "open circuit" position, and which, when erected or straightened, positively maintains the blade firmly against its contacts *i. e.*, in its 105 "closed circuit" position.

A quick break mechanically is especially aimed at in this embodiment and the construction is such that a spring under tension (augmented by the kick of the spring blade) 110 is abruptly rendered effective, without hindrance, to break the circuit by the instantaneous rebound of a suddenly released tensioned resilient blade. To that end, the erected toggle is arranged to hold the blade 115 flexed against the contacts, and a hand-operated lever providing sufficient "lost motion" to avoid hindrance is available to "break" the toggle and to erect the same. Thus, the lever O is pivoted to the stud x and provides two contact surfaces 70 and 71, the one or the other of which may be brought against some other part associated with the toggle to erect or to break it, as the case may be. These surfaces 70 and 71 are so spaced 120 as to provide sufficient lost motion to permit the handle 69 to move ineffectively through the major portion of its "breaking" stroke before the surface 70 will impact the toggle proper and so that only a slight continued 130

movement is necessary to break the toggle. The lever O is shown in dotted lines in Fig. 5 at the beginning of its breaking stroke and in full lines at the end of its breaking 5 stroke.

As shown by Fig. 5, therefore, the lever O in full lines is ready to be swung back to erect the toggle and close the circuit. When the lever O is thus returned, the finger or 10 contact portion 71 thereof bears against the rounded end of the floating link Q and swings the links P and Q into the dotted line positions. The links P and P' in this 15 form are arranged at either side of the links Q and Q', and the links P and P' are contoured to provide stop portion 74 and 75 adapted to limit the swing of the parts; the portion 75 being arranged to be arrested by impact with a suitable part immediately 20 after the axis W of the toggle has crossed its dead center and thus prevent any over-swing thereof. The floating link Q is pivoted at one end to the axis w and its other end is in any suitable manner connected to swing 25 the switch blade. In this form, this is achieved, by mounting the brush of a suitable cradle or other member R mounted to provide the necessary movement as, by means of being pivoted to the side v. This cradle 30 R is preferably made of sheet metal bent up in a U-shape and the links Q and Q' pass between the side walls of this cradle, and are connected to the shaft z which is secured between said side walls and which constitutes 35 a floating pivot of the toggle. A rather strong spring 76 has one end connected with a stud 77 on the stationary frame piece 61, and this other end bears against the cradle R so as strongly to urge the same into its 40 open circuit position and to be effective to do so whenever the toggle is broken. A spring 78 may in like manner bear against a pin 72 on the lever O as to lightly hold the lever in the dotted position when the toggle 45 is unbroken. The switch blade S is preferably constructed and mounted on the cradle R in the same manner as pointed out in connection with Fig. 3, and need not, therefore, be further described.

50 Without further analysis, the foregoing will so fully reveal the gist of this invention that others can by applying current knowledge readily adapt it for various applications without omitting certain features that 55 from the standpoint of the prior art, fairly constitute essential characteristics of the generic or specific aspects of this invention, and therefore such adaptations should and are intended to be comprehended within the 60 meaning and range of equivalency of the following claims.

Having thus revealed this invention, I claim as new and desire to secure the following combinations of elements, or equivalents

thereof, by Letters Patent of the United States:—

1. An inclosed switch box providing a compartment, having an overhanging cover ledge; a live conductor terminating at the under face of said ledge; a branch line terminal located in said compartment remote from said ledge; and a switch device adapted to be displaced as a unit from its normal position in said compartment, and thereby render dead said terminal, leaving said live conductor practically inaccessible located under said overhanging ledge. 70

2. A safety panel combining a box; a cover displaceably carried thereby; a switch mechanism carried by said cover and displaceable therewith; a branch-line terminal in said box; a fixed cover adjacent the displaceable cover; and a live conductor terminating near and beneath said fixed cover. 80

3. An inclosed switch mechanism of the nature disclosed combining a housing providing a compartment within which a switch blade may operate; conductors supported by said housing; a unitary switch mechanism detachably mounted by said housing and having its switch blade adapted to be actuated externally of said compartment; means for detachably retaining said switch mechanism whereby the same may be removed as a unit; and a stationary main-line terminal 90 so mounted in said housing as to be practically inaccessible when said switch unit has been removed. 95

4. A switch unit of the nature disclosed combining a frame adapting said unit to be detachably secured to a suitable support; a switch blade pivoted to said frame at one side of the normally exposed face thereof; blade operating mechanism also carried by said frame at the normally unexposed side 105 thereof; an operating handle for said mechanism located at the normally exposed side of said frame and extending therethrough into operative relation with said mechanism; and a stationary main-line terminal so mounted as to be practically inaccessible 110 when said switch unit has been removed. 115

5. An electrical switch mechanism combining a housing having a switch containing compartment; a conductor terminating in a contact piece within said compartment; a magnet in circuit with said conductor and having pole pieces adjacent said contact; and a removable switch unit separately mounted by said housing and providing a 120 switch blade, the construction being such that the spark will be magnetically blown out in the event of the operation or removal of said unit. 125

6. A switch mechanism combining a stationary base having an elevated overhanging lip; an elevated terminal closely underlying said lip so as to be practically inacces-

sible to the hands; a main cover adapted to be secured to said base; and a switch mechanism depending from said main cover so as to be removable as a unit, said mechanism 5 provided with a switch blade adapted to reach under said lip into contact with said terminal.

Copies of this patent may be obtained for five cents each, by addressing the "Commissioner of Patents, Washington, D. C."

In witness whereof, I hereunto subscribe my name, as attested by the two subscribing witnesses.
